UNITED STATES PATENT OFFICE.

THOMAS JAMES IRWIN, OF TRENTON, NEW JERSEY.

CUSHIONED HEEL.

1,109,757.

Specification of Letters Patent.

Patented Sept. 8, 1914.

Application filed November 3, 1913. Serial No. 799,046.

To all whom it may concern:

Be it known that I, THOMAS J. IRWIN, a citizen of the United States, and residing at Trenton, in the county of Mercer and 5 State of New Jersey, have invented certain new and useful Improvements in Cushioned Heels, of which the following is a specification, such as will enable those skilled in the art to which it appertains to make and use 10 the same.

This invention relates to cushions or resilient attachments for the heels of boots and shoes and it consists of improved means for securing a cushion of rubber or other 15 suitable material to the heel of a boot or shoe.

The invention is fully disclosed in the following specification of which the accompanying drawing forms a part, in which the 20 separate parts of my improvement are designated by suitable reference characters in each of the views, and in which;

Figure 1 is a bottom plan view of a heel provided with a rubber cushion attached according to my invention;—Fig. 2 a transverse section on the line 2—2 of Fig. 1;—Fig. 3 a section on the line 3—3 of Fig. 1;—Fig. 4 a bottom plan view of a cushion attaching clamp which I employ, and;—Fig. 30 5 a perspective view showing a modified form of said clamp.

In the drawing forming part of this specification, I have shown at a a boot or shoe heel composed of separate layers a^2 of 35 leather, and a cushion b of rubber.

In attaching the cushion b to the leather part of the heel, as shown in Figs. 1 to 4 inclusive, I provide a clamp device c , shown in transverse section in Fig. 2, in longitudinal 40 section in Fig. 3, and detached in Fig. 4.

The clamp device c is made of sheet metal and consists of a raised longitudinal central portion c^2 and depressed side flanges c^3 which are L-shaped in cross section, and in 45 the form of construction shown in Figs. 2 to 4 inclusive, a supplemental longitudinal plate c^4 is secured on the bottom of the part c^2 , and transversely corrugated, as clearly shown in said figures. The cushion b is also 50 provided centrally and longitudinally of the top thereof with a transverse depression b^2 adapted to receive the parts c^2 and c^4 of the clamp device c , and the bottom of which is transversely corrugated, as shown at b^3 , and 55 the cushion b is also provided at the oppo-

site sides of the transverse depression b^2 with longitudinal slits or slots b^4 , L-shaped in cross section and adapted to receive the side flanges c^3 of the clamp device c .

The transverse depression b^2 and the slits 60 or slots b^4 extend to and open through the front of the cushion b , but do not extend to and open through the back thereof, and in connecting the clamp device c with the cushion b and the cushion with the heel, the 65 clamp device is slid backwardly over the top surface of the cushion into position, in which operation the side flanges c^3 of the clamp device enter the slits or slots b^4 . It requires some force to do this, and when 70 the clamp device is fully in position, as shown in Fig. 3, the corrugations b^3 in the cushion b enter the corrugations c^4 in the part c^2 of the clamp device, and this aids in securing the clamp device to the cushion, 75 and the cushion is secured to the heel by passing screws d through holes d^2 in the cushion, and through the clamp device and into the part or parts a^2 of the heel.

My invention, however, is not limited to 80 the above described method of connecting the clamp device with the cushion and the cushion with the heel, and the clamp device may first be secured to the heel and the cushion moved backwardly into position, in 85 which operation the flanges c^3 of the clamp device would enter the slits or slots b^4 in the cushion, after which the screws d may be passed through the cushion and through the clamp device into the heel, or the clamp 90 device may be secured in the cushion in any preferred manner, or in any preferred way, and the cushion afterward secured to the heel, and in any event, the cushion, after it has been worn, may be substituted by a 95 new one in any of the ways above described.

In Fig. 5, I have shown a modification in which the transverse corrugations are formed integrally with the part c^2 of the clamp device, the distinctive feature of my 100 invention being in the form of the clamp device including the transverse corrugations, the side flanges c^3 which are L-shaped in cross section, the corresponding slits or slots b^4 in the cushion b , together with the 105 depression b^2 in the top of said cushion adapted to receive the parts c^2 and c^4 of the clamp device, and the screws d for securing the cushion to the heel.

Having fully described my invention what 110

I claim as new and desire to secure by Letters Patent is;—

The combination of a heel cushion and means for securing the same to a boot or shoe heel, said cushion having a longitudinal depression in the top thereof, and said longitudinal depression being provided in the bottom thereof with transverse corrugations, said cushion being also provided with side slits communicating with said longitudinal depression and L-shaped in cross section, and a clamp device consisting of a central longitudinal part arranged to fit in said lon-

itudinal depression and provided with transverse corrugations and side flanges 19 which are L-shaped in cross section and arranged to enter said slits.

In testimony that I claim the foregoing as my invention I have signed my name in presence of the subscribing witnesses this 20 31st day of October 1913.

THOMAS JAMES IRWIN.
